SLIDE STAND FOR CLOTH CUTTING MACHINES AND THE LIKE

Filed June 26, 1939

UNITED STATES PATENT OFFICE

2,211,082

SLIDE STAND FOR CLOTH CUTTING MACHINES AND THE LIKE

Pincus Smith, New York, N. Y.

Application June 26, 1939, Serial No. 281,095

6 Claims. (Cl. 164—77)

This invention relates to new and useful improvements in a slide stand for cloth cutting machines.

The invention has for an object the construction of a stand as mentioned which is capable of supporting a cloth cutting machine in a manner so that it may be freely moved forwards and rearwards, and so that it may be fixed in various lateral positions. But in all of these lateral positions it is still possible to move the cutting machine forwards and rearwards.

Another object of this invention resides in a provision of a scale arranged in a manner to guide the lateral placement of the cutting machine.

Still further the invention proposes a novel construction of a frame and mechanism associated therewith for the support of the cutting machine in an efficient way to accomplish the purposes of this invention.

Still further the invention contemplates a novel arrangement by which the cutting machine may be slightly moved laterally in a predetermined path without the necessity of an actual lateral adjustment of the machine.

Another object of this invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a slide stand and a cloth cutting machine associated therewith in accordance with this invention.

Fig. 2 is a fragmentary vertical sectional view taken on the line 2—2 of Fig. 1.

Fig. 3 is an end elevational view looking in the direction of the line 3—3 of Fig. 2.

Fig. 4 is a fragmentary vertical sectional view taken on the line 4—4 of Fig. 3.

Fig. 5 is a fragmentary plan view looking in the direction of the line 5—5 of Fig. 3.

Fig. 6 is a fragmentary vertical sectional view taken on the line 6—6 of Fig. 5.

Fig. 7 is a fragmentary transverse sectional view taken on the line 7—7 of Fig. 2.

Fig. 8 is a fragmentary plan view looking in the direction of the line 8—8 of Fig. 7.

Fig. 9 is a fragmentary vertical sectional view taken on the line 9—9 of Fig. 8.

Fig. 10 is a fragmentary sectional view similar to Fig. 2 but illustrated on a modified construction of the invention.

Fig. 11 is a fragmentary sectional view taken on the line 11—11 of Fig. 10.

Fig. 12 is a fragmentary plan view looking in the direction of the line 12—12 of Fig. 10.

A slide stand for cutting machines in accordance with this invention includes a cutting table 15 upon which there is fixedly mounted spaced parallel tracks 16. A frame is superimposed on the table and extends between the tracks 16 and is provided with wheels 17 engaging the tracks in a manner so that the frame may be moved forwards and rearwards. This frame also includes a lateral extending rod 18.

The frame mentioned in the previous paragraph consists of a pair of end units held in fixed spaced positions by the rod 18 and auxiliary rods 19. Each end unit has a bottom horizontal bar 20 upon the ends of which, the wheels 17 are mounted. The bars 20 are connected with vertical bars 21 and with upwardly converging bars 22. The bars 21 and 22 meet at the common point at which point the rod 18 is supported. Another horizontal bar 23 is contained in each end unit and is spaced slightly above the bar 20.

The rods 19 are mounted upon the ends of the bars 23. A spacer plate 24 is superimposed between the upper ends of the bars 21 and the bars 22 to compensate for the thickness of the bars 23. A plurality of bolts 25, as illustrated in Figs. 1 to 4 serve to hold the various bars of each end unit fixedly together. Each of the wheels 17 is provided with a flange 17a engaging the outer edge of the track. In this way the frame is firmly held upon the tracks so as to be capable of being moved forwards and rearwards only. Each end unit is also provided with a rearward extending horizontal bar 26 supported at its front end by nuts 27 mounted upon the ends of the rod 18. The rear portion of each horizontal bar 26 is provided with a U-shaped section 28. A fastening band 29 engages over each U-shaped section 28 for closing the open end of the U-shaped sections. A scale bar 30 is supported on its ends on the U-shaped sections 28 and is fixedly held by clamp screws 31 which threadedly engage through the rear arms of the U-shaped sections and which have their inner ends abutting and firmly holding the bar 30.

A collar 32 is slidably mounted on the rod 18. 55

A collar 32 is slidably mounted on the rod 18. 55

Several handle controlled clamp screws 33 are mounted upon the collar 32 and are capable of abutting the rod 18 for holding the collar in desired fixed positions. A horizontal plate 34 is supported upon the collar 32 preferably by welding or other means. This plate is arranged so that substantially half of the plate extends to the front of the collar and the other half to the rear. A cutting machine 35 is disposed beneath the plate 34 and is provided with long supporting bolts 36 extending upwards and through the plate 34 so that the cutting machine may be lifted when desired. More specifically the bolts 36 are threadedly engaged at their bottom ends into the body of the cutting machine 35. The top ends of the bolts pass through openings in the plate 34. Each bolt has a head 36^a at its upper end which normally abuts the top face of the plate 34, to support the cutting machine in a predetermined lowered position. The arrangement is such that when desired the cutting machine 35 may be lifted bodily upwards and then the bolts 36 will merely extend upwards through the plate 34.

An indicator finger 37 is fixedly mounted on the plate 34 and extends over a scale 39 imprinted upon the bar 30. A bracket 40 is also mounted upon the plate 34 and supports an electric light 41.

The operation of the device is as follows: A stack of cloth to be cut is placed on the table 15. Then the screws 33 are loosened so that the cutting machine may be shifted laterally relative to the frame. The collar 32 merely slides along the rod 18. It is also possible to lift the cutting machine, the bolts 36 idle through the plate 34, so that the cutting machine may be placed upon the cloth goods to be cut. When the cutting machine is in the proper lateral position, the screws 33 are tightened to hold it fixed laterally. It is now possible to move the cutting machine forwards or rearwards with the frame moving along the tracks 16. In this way it is possible to cut the cloth in a predetermined straight line.

In the Figs. 10 to 12 inclusive, a modified form of the invention has been disclosed which distinguishes from the prior form essentially in the way the cutting machine is supported. In this form of the invention the cutting machine 35 is supported by several bolts 36'. These bolts have heads 36^{aa} at their bottom ends, and nuts or heads 36^a at their top ends. The bolts 36' slidably engage through the body portion 35' of the cutting machine, so that the cutting machine 35 may be lifted and the body portion 35' will slide up upon the bolts 36'.

The upper ends of the bolts 36' pass through openings 42 formed in the plate 34'. This plate is supported upon the collar 32 which may be held in various fixed positions by the screws 33. The collar 32 is slideable upon the rod 18. Members 43 are hingedly mounted on their inner ends by hinges 44 upon the collar 32. Springs 45 are coaxially arranged on the hinges 44 and act to normally pivot the outer ends of the members 43 downwards. The outer ends of these members engage against the heads 36^a of the bolts 36'. The members 43 act to normally hold the bolts 36' in fixed positions in the openings 42. The openings 42 are shaped so as to have lateral extending portions and forward or rearward extending portions depending upon the particular design desired.

In other respects this form of the invention is identical to the prior form and identical parts

have been indicated by the same reference numerals.

The operation of this form of the invention is similar to the prior form. When desired the cutting machine 35 may be lifted upwards by the body 35 sliding on the bolts 36' and the cutting machine may be shifted laterally by the collar 32 moving along the rod 18. If it is desired to move the cutting machine 35 slightly laterally or forwards or rearwards depending upon the design of the openings 42, without disturbing the adjustment or position of the collar 32 on the rod 18 it is merely necessary to lift the cutting machine 35 and then to manually force the cutting machine so that it moves, with the bolts 36' moving in the slots 42. The members 43 will hold the bolts in their newly acquired positions.

It is to be understood that this device may be used in connection with any cutting machine, for cutting any other material, such as wood, composition, leather, etc.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A slide stand for cloth cutting machines, comprising a cutting table, spaced parallel tracks mounted thereon, a frame superimposed on said table and extending between said tracks and having supporting wheels mounted thereon and engaging said tracks so that the frame may be moved forwards and rearwards and also having a laterally extending rod, a collar mounted on said rod, means for holding said collar in fixed positions on said rod, a plate supported in said collar, and a cutting machine beneath said plate and having long bolts extending through said plate so that the cutting machine may be lifted.

2. A slide stand for cloth cutting machines, comprising a cutting table, spaced parallel tracks mounted thereon, a frame superimposed on said table and extending between said tracks and having supporting wheels engaging said tracks so that the frame may be moved forwards and rearwards and also having a laterally extending rod, a collar mounted on said rod, means for holding said collar in fixed positions on said rod, a plate supported in said collar, and a cutting machine beneath said plate and having long bolts extending through said plate so that the cutting machine may be lifted, said frame having end units each including a body horizontal bar upon which said wheels are mounted, and vertical extending bars upon which other horizontal bars are mounted, said latter bars being connected with each other by spacer rods.

3. A slide stand for cloth cutting machines, comprising a cutting table, spaced parallel tracks mounted thereon, a frame superimposed on said table and extending between said tracks and having supporting wheels engaging said tracks so that the frame may be moved forwards and rearwards and also having a laterally extending rod, a collar mounted on said rod, means for holding said collar in fixed positions on said rod, a plate supported in said collar, and a cutting machine beneath said plate and having long bolts extending through said plate so that the cutting machine may be lifted, said means for holding

the collar comprising screws threadedly engaged through the collar and abutting said rod.

4. A slide stand for cloth cutting machines, comprising a cutting table, spaced parallel tracks mounted thereon, a frame superimposed on said table and extending between said tracks and having supporting wheels engaging said tracks so that the frame may be moved forwards and rearwards and also having a laterally extending rod, a collar mounted on said rod, means for holding said collar in fixed positions on said rod, a plate supported in said collar, and a cutting machine beneath said plate and having long bolts extending through said plate so that the cutting machine may be lifted, said plate having slots through which the bolts pass, said bolts being slidably mounted through said slots and being slidably mounted through the body and said cutting machine, and means for holding said bolts in fixed positions in said slots.

5. A slide stand for cloth cutting machines, comprising a cutting table, spaced parallel tracks mounted thereon, a frame superimposed on said table and extending between said tracks and having supporting wheels engaging said tracks so that the frame may be moved forwards and rearwards and also having a laterally extending rod, a collar mounted on said rod, means for holding said collar in fixed positions on said rod, a plate supported in said collar, and a cutting machine beneath said plate and having long bolts extending through said plate so that the cutting ma-

chine may be lifted, said plate having slots through which the bolts pass, said bolts being slidably mounted through said slots and being slidably mounted through the body and said cutting machine, and means for holding said bolts in fixed positions in said slots, comprising members hingedly mounted upon said collar and resiliently urged against the upper ends of said bolts.

6. A slide stand for cloth cutting machines, comprising a cutting table, spaced parallel tracks mounted thereon, a frame superimposed on said table and extending between said tracks and having supporting wheels engaging said tracks so that the frame may be moved forwards and rearwards and also having a laterally extending rod, a collar mounted on said rod, means for holding said collar in fixed positions on said rod, a plate supported in said collar, and a cutting machine beneath said plate and having long bolts extending through said plate so that the cutting machine may be lifted, said plate having slots through which the bolts pass, said bolts being slidably mounted through said slots and being slidably mounted through the body and said cutting machine, and means for holding said bolts in fixed positions in said slots, comprising members hingedly mounted upon said collar and resiliently urged against the upper ends of said bolts, by springs acting between said members and hinge points.

PINCUS SMITH.
